JOHN M. HOTHERSALL, OF BROOKLYN, NEW YORK, ASSIGNOR TO AMERICAN CAN COMPANY, OF NEW YORK, N. Y., A CORPORATION OF NEW JERSEY

SEALING RING AND METHOD OF MAKING IT

Application filed March 22, 1928. Serial No. 263,678.

This invention relates in general to containers and closures therefor, and has more particular reference to a cover sealing ring with lapped ends and the method of making it.

A sealing ring with lapped ends, which is completely formed before being applied to use, to be the most effective should have interior and exterior surfaces of uniform dimensions throughout, as this gives it a uniform clamping engagement with the cover and the container parts. Such a ring may be positioned in any circumferential part of the assembling die, and the overlapped portion may be placed in any position engaging the container and cover without the necessity of an accurate and tedious alinement of the ring for engagement either with the container parts or the closure die.

An important object of this invention is to provide such a sealing ring with overlapped ends which has uniform interior and exterior dimensions.

Another important object is the provision of a method of producing such a ring from a strip of sheet metal.

A further object of the invention is the provision of a sealing ring which has corrugations defining the exterior or interior dimensions of the ring, the corrugations being interlocked and ironed out smoothly where the ends are lapped, whereby the double thickness is not greater than a single thickness through the corrugations.

A further object of the invention is the provision of a die mechanism adapted to form such a ring with lapped ends, the die being capable of forming the lap irrespective of the position of the strip therein.

Numerous other objects and advantages of the invention will be apparent as it is better understood from the following description, which, taken in connection with the accompanying drawings, discloses a preferred embodiment thereof.

In the drawings:

Figure 1 is a perspective of a corrugated strip arranged in circular form ready for application to the die forming mechanism.

Fig. 2 is a perspective of a sealing ring

produced in accordance with this invention;

Fig. 3 is a sectional view of die members for forming the ring as arranged just prior to the forming operation;

Fig. 4 is a fragmentary view of the formed ring between the die members, as taken upon a line 4-4 of Fig. 6, through the overlapping portion;

Fig. 5 is a similar fragmentary view, as taken on the line 5-5 of Fig. 6, through a portion which does not overlap;

Fig. 6 is a perspective of a part of the formed ring at the overlapping portions, and

Fig. 7 is a diagrammatic view illustrating the different states of development of the ring.

Referring more particularly to the drawings, reference character 10 indicates a strip of sheet metal in which a top edge 11 and bottom edge 12 are slightly curved in opposite directions and in which corrugations 13 are formed adjacent the top edge 11, the corrugations having a depth substantially equal to the gauge of the strip. This strip is adapted to be bent or formed with the ends 14 overlapping for a distance embracing a number of the corrugations 13.

The completed annular or circular strip is readily formed in a die, and in Fig. 3 I show a die adapted to perform the forming operation. A die head 15 is movable to and from a fixed bed plate 16, the head and bed plate cooperating to form the sealing strip in a manner to be explained later. The die head 15 carries a forming ring 18 slidable upon a reduced portion of the head, the forming ring being retained in position by a holding ring 19 secured to the head by bolts 20. The forming ring 18 is normally pressed downwardly from the die head by stiff springs 21, its downward movement being limited by an annular projection 22 cooperating with an annular shoulder in the holding ring 19. The lower surface of the ring 18 is formed with a depending ridge 33 around its outer periphery, the ridge being U-shaped in cross-section. A curling depression 34 is formed just inside this ridge, and a flat contact surface 35 completes the lower edge of the ring.

The bed plate 16 is supported upon a spin-

die 17 which extends into the bed of the press. A fixed forming ring 24 is positioned upon the bed plate 16 secured thereto by a holding plate 25 and bolts 26. The bed plate 16 has an annular recess 27 near the outer side of the forming ring which is adapted to receive a movable forming ring 28. In the forming ring 24 adjacent the recess 27 a second smaller recess 32 is formed inwardly from the recess 27 and is adapted to cooperate with the ridge 33 on the head forming ring 18 in a spaced relationship, that is, the ridge 33 does not completely fill the depression 32 when the two are brought into engagement. The movable forming ring 28 is supported in the recess 27 of the fixed ring by bolts 29, which extend into a plate 30 below the bed plate 16, the plate 30 being supported upon a buffer 31 of resilient material. Upward movement of the movable ring 28 is limited by an annular projection 50 engaging a shoulder 51 formed in a fixed ring 24 which surrounds the recess 27. The movable ring 28 is formed with a curling recess 38 adjacent its inner, upper periphery, this recess registering with a similar recess 37 formed in the holding ring 19 on the die head. A portion 36 of the fixed ring 24 provides a flat contact surface which registers with the recess 34 formed in the upper movable forming ring 18.

The steps of forming the completed sealing ring by this die are clearly illustrated in Fig. 7. The strip, as shown in Figure 1, is placed with the lower curved edge 12 within the recess 32 of the lower fixed plate 24. As the head 15 descends, the forming ring 18 in its lower position presses the strip against the lower movable forming ring 28, interlocking the corrugations 13 where the ends of the sealing band overlap, compressing them and ironing them out smoothly (see "A" Fig. 7). Further downward movement compresses the springs 21, allowing the holding ring 19 to come into contact with the lower movable ring 28 forming a continuous circular bead or curl 39 from the upper edge 11 of the strip within the registering curling recesses 37 and 38 (see "B" Fig. 7).

Further downward movement forces the strip edgewise through the recess formed between the ridge 33 and the recess 32 and bends it upward to form a U (see "C" Fig. 7). Still further downward movement brings the curling groove 34 in the ring 18 into registration with the contact surface 36 of the ring 24, forming a second bead or curl 41 from the edge 12 of the strip (see "D" Fig. 7). This completes the forming process and the head 15 is moved out of engagement with the head plate 16, the forming ring 18 returning to its normal position under the action of the springs 21.

As shown more clearly in Figs. 4 and 5, it is necessary to provide a space between the

die members equal substantially to twice the thickness of the strip itself throughout the entire circumference of the die members, in order to insure that the finished sealing ring will have uniform internal and external diameters throughout, even including the overlapping portion designated by the reference numeral 42 in Fig. 2, in which portion the corrugations 13 are smoothed or ironed out. The reason for this is clearly apparent from Fig. 4, in which there are two thicknesses of material for the entire cross-section, including both curls 39 and 41, and the U-shaped section 40. This necessitates that the corrugations 13 be offset from the face of the strip 10 an amount substantially equal to the thickness of the strip, so that when the overlapped portions of the strip are compressed, ironing out the corrugations, the overlapped portion will be the same outside diameter as that defined by the outer engaging portions of the corrugations 13. This insures that the exterior and interior diameters of the formed ring will be uniform, presenting no uneven portions, even where the ends of the strip are overlapped for the proper engagement and application of the sealing ring.

It is thought that this invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A sealing ring comprising a strip of sheet metal, said strip having a corrugated portion and having overlapping ends, the corrugations on the overlapped end portion being flattened out.

2. A circular sealing strip with overlapped ends having corrugations of substantially the thickness of the material of the strip, the corrugations being ironed out in the overlapping portions to maintain the inner and outer effective dimensions of the ring uniform throughout.

3. A circular sealing strip with overlapped ends, a portion of the strip having corrugations of a depth substantially equal to the gauge of the metal, the corrugations of the overlapped portions being interlocked and smoothed out to maintain a uniform thickness of metal.

4. A circular sealing strip of U-shaped cross-section with overlapped ends, one leg of the U having corrugations of a depth substantially the gauge of the metal, the corrugations in the overlapping ends being interlocked and ironed out to provide a ring of uniform interior and exterior diameters.

5. A circular sealing strip of U-shaped

cross-section with uniform interior and exterior diameters, said strip having a smooth portion where the ends are overlapped and joined, the remainder being corrugated, said 5 corrugations having a depth substantially the gauge of the metal.

6. The method of forming sealing rings, which comprises overlapping the ends of a partially corrugated strip of sheet metal, and 10 then compressing the overlapped portions to iron out the corrugations.

7. The method of forming a lap ended sealing ring of uniform inner and outer dimensions, from a corrugated strip of sheet 15 metal, which consists in compressing the overlapped portions to interengage and iron out the corrugations to the inner and outer dimensions of the remainder of the ring.

8. The method of forming sealing rings, 20 which consists in overlapping the ends of a partially corrugated strip of sheet metal in circular form, forcing the strip edgewise, forming the strip with a curl at its upper edge, an upright U-shape in its intermediate 25 part, and a curl at the other edge and compressing the corrugations in the overlapped portion.

9. The method of forming sealing rings 30 from a partially corrugated strip of sheet metal, which consists in overlapping the ends of the strip in circular form, in interlocking and ironing out the corrugations in the overlapping portion, in forcing the strip edgewise and forming the strip with curls at its 35 edges and U-shaped under its intermediate part, thereby producing a circular U-shaped ring, curled at both edges and of uniform inner and outer dimensions.

10. The method of forming sealing rings 40 from corrugated sheet metal strips, which consists in bending the strips to annulate form with the ends overlapping and the corrugations interengaging, in compressing the overlapped end portions to iron out the 45 corrugations in the overlapping portions in forming the upper edge into a cylindrical curl extending around the strip, forcing the strip edgewise to form it into an upright, U-shaped cross-section, forcing the inner 50 edge of the strip into a cylindrical curl, thereby producing a circular U-shaped strip curled at both edges, having overlapped ends, and uniform inside and outside dimensions throughout.

55. 11. A sealing ring blank to secure together container parts, comprising, a strip of sheet metal bent to form an annular body with overlapping ends, said body being corrugated throughout its circumference, the corruga- 60 tions of one end of said body interlocking with the corrugations of the other end.

12. The method of forming sealing rings to secure together container parts, which 65 consists of bending a substantially flat strip into an annular blank with overlapped ends,

and forcing said blank through forming dies to form a channelled annular body.

13. The method of forming sealing rings to secure together container parts, which consists of bending a substantially flat strip 70 into an annular blank with overlapped ends, forcing said blank through forming dies to form a channelled annular body, and curling the free edges of said body.
